UNITED STATES PATENT OFFICE

2,542,840

GUARDRAIL ASSEMBLY

George H. Riddle, Bethlehem, Pa., assignor to
Bethlehem Steel Company, a corporation of
Pennsylvania

Application April 24, 1946, Serial No. 664,535

4 Claims. (Cl. 238—17)

1

My invention relates in general to railway track equipment, and more particularly to an improved guard rail assembly.

It is conventional railroad practice, at places such as switches, frogs and curves where there may be some possibility of derailments, to employ inner guard rails adjacent to and parallel to a main rail to hold the wheel-flanges against the main rail. In this service it is obvious that safety is essential.

One object of this invention, therefore, is to provide a guard rail assembly of increased reliability, adaptability, and sturdiness.

A further object is to provide an assembly with positive resistance to creeping under continued heavy traffic.

A further object is an assembly which is adapted to the use of lateral braces where required.

A further object is an assembly requiring a minimum of machining in order to permit a vertical or canted main rail to be used.

A further object is an assembly in which the wheel flangeway may be readily adjusted to compensate for gaging or wear by the movement of only one rail plate.

Another object is an assembly in which the lateral pressure on the guard rail tending to overturn it is simultaneously opposed by the downward pressure on the main rail.

Still another object is a welded and bolted assembly in which the double side shoulders provide a strong and rigid clamping effect, with resultant resistance to lateral thrusts and easier maintenance of alignment.

Other and further objects, advantages and purposes of this invention will appear hereinafter in the specification and in the appended claims.

In order to render my invention more clear, I shall now refer to the attached sheet of drawings forming a part of this specification and in which like figures of reference indicate like parts.

Figure 1 is a reduced-scale top plan view of a guard rail assembly constructed in accordance with the present invention;

Fig. 2 is a considerably enlarged vertical transverse section, taken on the line 2-2 of Fig. 3;

Fig. 3 is a somewhat enlarged top plan view of the central portion of the assembly shown in Fig. 1, and

Fig. 4 is a fragmentary vertical transverse section showing how the clip, the main rail tie plate and the reinforcing plate are bolted together.

Referring to the drawings, the numeral 1 designates the main rail, preferably of stand-

ard T shape as shown; and 2 the guard rail, which may have beveled end faces as shown in Fig. 1. The head 3 of said guard rail may for increased service have the greater portion of the metal disposed on its outer or wheel-flange engaging side 4 as shown. The base of said guard rail is provided with a flat inner flange 5 of substantially standard shape, and with an outwardly projecting and downwardly inclined hook flange 6.

Each rolled steel guard rail plate 7 is provided with a shoulder 8 abutting the edge of the inner flange 5 of the guard rail, and with a seat 9 having a longitudinal recess 10 and adapted to receive the hook flange 6. A pair of inclined braces 11 having their upper ends abutting the head 3 and web 12 of the guard rail 2 and welded at their lower base edges by seams 13 to the guard rail plate 7 may be employed to provide additional strength in the center of said guard rail.

The main rail 1 is seated on the bridging tie plates 14, each of which is provided with a shoulder 15 abutting the edge of the outer flange 16 of said main rail 1. The inner flange 17 of said rail 1 is arranged and adapted to overhang the short inner side 18 of the tie plate 14 and to rest upon the outer hook flange 6 of the guard rail 2 to prevent its overturning. The seat of said tie plate 14 may be canted, to accommodate a canted main rail as shown in Fig. 2, or planed flat to accommodate a vertical rail whichever may be desired.

A narrow rectangular transverse base plate 19 is secured centrally beneath each guard rail plate 7 by the welded seam 20 and may be similarly secured to main rail tie plate 14 if an integral non-adjustable assembly is desired. However, it may at times be necessary to compensate for rail wear and other changes in conditions of operation by the adjusting means shown, comprising a pair of standard button head oval neck track bolts 21 passing upward through the diagonally disposed elliptical slots 22 in said base plate 19 and through the corresponding round holes 23 in the tie plate 14 and the elliptical holes 23' in the clip 24 bearing against the outer flange of the rail 1, said bolts being retained in place by lock-washers 24' and nuts 25. In cooperation therewith, the diagonally inclined outer shoulder 26 of the base plate 19 fitting into the somewhat wider and similarly inclined cut-away outer portion 27 of the tie plate 14 allows the flangeway between the rails to be readily made wider or narrower by a simple sliding motion of the tie

plate 14 on the base plate 19 without the risk of accidental spreading of the rails.

The base plates 19, the guard rail plates 7, and the inner flange 5 of the guard rail 2 are each provided with registering transverse bolt holes through which pass the pair of track bolts 28 secured by washers 29 and 30 and nuts 31. A plurality of punched square holes 32 in each guard rail plate 7 and tie plate 14 allows said plates to be secured by the spikes 33 to the adjacent supporting ties 34, between which, and generally without touching said ties, the base plate 19 is held suspended.

When I use the expression "outer" throughout the specification and claims I mean the location outside of the track structure and when I use the expression "inner" I mean the location within the main track structure.

Although I have hereinabove shown and described my invention in considerable detail, I do not wish to be limited to the exact and specific structures stated, but may use such substitutes, modifications or equivalents thereof as are within the scope and spirit of the invention and of the appended claims.

Having thus described my invention, what I claim as new and useful and desire to protect by Letters Patent is:

1. In a guard rail assembly, the combination of a main rail, a guard rail having its outer flange underlying the inner flange of the main rail, a guard rail plate and a separate main rail tie plate seating said rails respectively, a base plate affixed to the guard rail plate and provided with a longitudinally inclined outer shoulder which engages a corresponding recess in the main rail tie plate, and upright headed members movable in slots in the base plate spaced inward from and parallel to said outer shoulder and extending upward through bolt holes in the tie plate, and thereby permitting the relative adjustment of spacing between main rail and guard rail and securing of said tie plate to the base plate.

2. In a guard rail assembly, the combination of a base plate having an inwardly sloping outer shoulder and correspondingly sloping elliptical slots adjacent said shoulder, a tie plate having its outer face centrally recessed to engage said shoulder and having bolt holes registering with the elliptical slots, bolts slidably securing the tie plate upon the base plate, a main rail seated on said tie plate, a guard rail plate secured to the base plate, and a guard rail seated parallel to the main rail on said guard rail plate.

3. In a guard rail assembly, the combination of a main rail, a tie plate seating said rail and provided with bolt holes and a diagonally sloping cut-away outer portion, a clip bearing against the outer flange of said rail, a guard rail parallel

to the main rail, a guard rail plate seating said guard rail, a base plate extending centrally beneath the tie plate and guard rail plate and welded to the latter, said base plate being provided with diagonally sloping oval slots in register with the bolt holes of the clip and tie plate and with a diagonally sloping shoulder fitting into the cut-away portion of said tie plate, and tie-bolts inserted through said bolt holes and said oval slots.

4. In a guard rail assembly, the combination of a guard rail provided with an inner flange of substantially standard shape and with an outwardly projecting and downwardly inclined hook flange, a guard rail plate provided with a shoulder abutting the inner flange of the guard rail and having a seat adapted to receive the hook flange thereof, inclined braces having their upper ends abutting the web of the guard rail and welded at their lower base edges to the guard rail plate, a main rail of standard shape spaced outwardly of and parallel to the guard rail and having its inner flange resting upon the outer hook flange of said guard rail, a tie plate seating said main rail and provided with an inner shoulder abutting the outer flange of said main rail and an outer recessed portion having a face inclined at an acute angle to the longitudinal axis of said main rail, a clip bearing against said outer flange, said guard rail plate and tie plate being adapted to span a pair of railroad ties, and a base plate having a terminal shoulder of corresponding angle but shorter than the recess and engaging therein adapted to be interposed between said ties and secured beneath the guard rail plate and the tie plate, whereby longitudinal movement of the base plate and main rail tie plate with reference to each other will cause said tie plate and the guard rail plate to approach toward or recede from each other.

GEORGE H. RIDDLE.
